CLAIM

The ornamental design for a cleaning mitt, as shown and described.

DESCRIPTION

FIG. 1 is an isometric view, from the top, front and one side of a cleaning mitt showing my new design; and, FIG. 2 is a bottom plan view thereof.

The view of the back and the other side is the same as the view of the front and the one side.

The stippling in FIGS. 1-2 represents a somewhat rough, terrycloth-like surface.

The mesh in FIGS. 1-2 represents a mesh netting constituting the outer scrubbing surface of the mitt.

The cloth loop indicated in dotted line in FIGS. 1-2 represents only an environment of use and forms no part of the claimed design.
